UNITED STATES PATENT OFFICE.

JACOB HOWARD MARK, OF HERKIMER, NEW YORK, ASSIGNOR TO MARK MANUFACTURING COMPANY, OF HERKIMER, NEW YORK, A CORPORATION OF NEW YORK.

JACKET.

No. 848,669.

Specification of Letters Patent.

Patented April 2, 1907.

Application filed March 24, 1906. Serial No. 307,815.

To all whom it may concern:

Be it known that I, JACOB HOWARD MARK, of Herkimer, New York, have invented a new and useful Improvement in Jackets, which invention is fully set forth in the following specification.

My invention relates to knit garments having the general characteristics of "cardigan" jackets, and has for its object to provide such a garment with a collar which may be cheaply and expeditiously manufactured and attached to the jacket, which may be worn in a turned-down position, when it constitutes a slightly-rolled collar, or worn in a turned-up position, when it protects the throat in the same manner as does the usual sweater-neck, and, further, to provide such a collar that when the jacket is buttoned up the end portions thereof will constitute an effective and efficient chest-protector. These objects are attained by suitably securing to the jacket in place of the ordinary collar a strip of the usual sweater-neck material (preferably a continuous piece) of substantially equal width throughout, the end portions of said strip extending down the face of the jacket a suitable distance.

The invention will be better understood by reference to the accompanying drawings, wherein—

Figure 1 shows a perspective view illustrating a jacket with the improved collar shown in its turned-down position. Fig. 2 is a view showing the collar in its turned-up position. Fig. 3 is a perspective view showing a portion of the inside of a jacket with the collar fixed thereto; and Fig. 4 is a transverse sectional view through the collar, illustrating the method of affixing the same to the jacket.

Referring to the drawings, 1 is the body part of a usual cardigan jacket made in the regular manner, the jacket herein illustrated being of the double-breasted type with two rows of buttons 2 on the outside of the jacket and two rows of buttons 3 on the inside of the jacket. Preferably there is an equal number of buttons both inside and outside, the same being secured together in pairs by 50 thread passing through the material of the jacket. The buttons are thus effectively

and fixedly secured to the jacket, and the inside buttons may, if desired, be engaged with the buttonholes of the overlapped portion of the jacket when the latter is buttoned. The 55 buttonholes are preferably reinforced and protected by pieces 4 and the opening of the jacket by a strip of braid 5.

In manufacturing the jacket herein illustrated the portion of material that ordinarily constitutes the collar is cut away, the configuration of the cut being indicated by the dotted line 6 in Fig. 3 and in its place is secured collar 7, which is attached to the jacket in any suitable or desired manner. 60 This collar consists of a piece of woven fabric, such as knit material; but preferably I use a tubular piece of seamless ribbed sweater-neck material which is knit on the usual necking-machine, the ribs of said piece running longitudinally of the collar. As indicated in the present embodiment, the collar 7 is secured to the neck portion of the jacket by stitches 8, passing through the body of the jacket and braid 5. The ends 9 of the collar 75 are preferably extended down the face of the jacket, the inner edges 10 of these end portions being also suitably secured to the jacket, as by sewing-stitches. Extending the end portions of the collar down the face of the 80 jacket a suitable distance not only permits the collar to be more fixedly secured to the jacket, but when the jacket is buttoned up these end portions rest side by side, as shown in dotted lines in Figs. 1 and 2, and an additional protection to the chest of the wearer is afforded.

It will therefore be seen that I have provided a garment which embodies the desirable features of both a jacket and a sweater, 90 a garment which may be worn open when the wearer is exercising and closed when needed as a protection for the chest, a garment which constitutes a slightly and attractive jacket and which permits the collar and tie of the 95 wearer to be visible, thus making a neat appearance, and, further, a garment which while embodying all the desirable features of the usual "sweater" by reason of the collar when turned up falling closely and snugly 100 around the neck does not have to be slipped over the head of the wearer.

What is claimed is—

A body-garment having a roll-collar of substantially the same width throughout formed of a tubular seamelss piece of ribbed material secured to said garment, said collar in its turned-up position overlapping and

5

protecting the throat of the wearer.

In testimony whereof I have signed this specification in the presence of two subscribing witnesses.

JACOB HOWARD MARK.
